MEANS FOR HANDLING PAPER ON
BUSINESS MACHINES

Clayton E. Wyrick, Miami, Fla., assignor to The
Egry Register Company, Dayton, Ohio, a cor-
poration of Ohio

Application July 20, 1942, Serial No. 451,645

21 Claims. (CL 197—126)

This invention relates to paper and carbon feeding mechanism adapted for use in combination with a printing or typing machine. More particularly, the invention relates to an apparatus for controlling the movement of carbon sheets with respect to a plurality of continuous webs of paper which is fed through a typewriter in a manner that the carbon sheets can be used many times for reproducing copies of information typed upon the paper webs.

The carbon feeding apparatus is constructed and arranged so that the carbon sheets can be fed through the typewriter with the plurality of continuous paper webs for reproducing information upon the webs. After the desired information has been typed the paper webs and the carbon sheets are moved rearwardly out of the typewriter and the carbon sheets are retained by suitable mechanism so that the paper webs alone can be advanced through the typewriter to permit removal of the portion of the paper webs which has the information typed thereon. After a predetermined length of paper web has passed through the carbon feeding mechanism the carbon sheets will be released to permit the same to advance with the paper webs so that when the portion of the webs has been removed upon which information has been typed the paper webs and the carbon sheets will be in position for subsequent typing operation. The apparatus is especially adapted for typing information upon repeated forms printed upon the face of continuous webs, such as multiple bill forms.

An object of the invention is to provide a carbon feeding attachment for a printing or typing machine wherein the movement of the carbon is automatically controlled.

Another object of the invention is to provide an improved carbon feeding attachment which is adapted to release the carbon to permit the same to move forwardly between a plurality of adjacent paper webs after a determined length of paper web has passed through the carbon feeding attachment.

Another object of the invention is to provide a carbon feeding attachment for printing or typing machines wherein the forward movement of the carbon sheets is controlled by a predetermined length of paper web passing through the carbon feeding attachment and the rearward movement of the carbon sheets with respect to the typing machine conditions a mechanism for measuring a length of paper web passing therethrough.

Another object of the invention is to provide an improved automatic carbon feeding apparatus for attachment to a conventional typewriter or printing machine which relieves the operator of substantially all manual manipulation of the carbon feeding apparatus.

Another object of the invention is to provide a carbon feeding apparatus for use in combination with a typewriter having means to isolate the movement of the main frame of the carbon feeding apparatus from the movement of the carriage of the typewriter to prevent the movement of the typewriter carriage from being directly transmitted to the carbon feeding apparatus.

Another object of the invention is to provide a carbon feeding apparatus for a typewriter which is constructed and arranged to permit the typewriter to be used for normal typing operations without removing the carbon feeding apparatus from the typewriter.

Another object of the invention is to provide a mechanism for longitudinally aligning form faces printed on superposed continuous webs by engaging a weakened line, such as a perforation line or fold line, extending transversely of the webs after completing preparation of one of the form faces so that the subsequent form faces on superposed webs will be aligned just prior to their use in a typing machine with which the aligning mechanism is associated; the fold line or perforation line also being used as a tear off line so that each form face can be separated from the continuous web, the aligning means also providing means for separating the completed form faces from the continuous web.

Further objects and advantages will become apparent from the drawings and the following description.

In the drawings:

Figure 1 is a side elevational view of a typewriter having the carbon feeding attachment of this invention associated therewith.

Figure 2 is a top plan view of the carbon feeding attachment shown in Figure 1.

Figure 3 is a bottom plan view of the carbon feeding attachment shown in Figure 1, the portion thereof which is adapted to be associated with the platen of the typewriter is removed.

Figure 4 is a longitudinal cross-sectional view of the carbon feeding apparatus taken along line 4—4 of Figure 2, and shows the relative position of the typewriter platen with respect to the carbon feeding apparatus.

Figure 5 is a perspective elevational view show-

ing a portion of the operating mechanism for controlling movement of the sheets as viewed from the underside of the apparatus.

Figure 6 is a somewhat schematic view of the operating mechanism of the carbon feeding apparatus shown in position with the carbon sheets released to permit a typing operation upon the typewriter.

Figure 7 is a schematic view similar to Figure 6 but shows the operating mechanism in position caused by the return movement of the carbon sheets.

Figure 8 is a schematic view similar to Figure 6 but shows the operating mechanism in position wherein the carbon sheets are retained in stationary position to permit the paper webs to be moved with respect to the carbon sheets.

Figure 9 is a schematic view similar to Figure 6 but shows the operating mechanism in position wherein movement of the paper webs through the machine has just caused release of the carbon sheets.

Figure 10 is a schematic view similar to Figure 6 but shows the operating mechanism in position to permit the paper webs, which have been typed, to be torn from the main body of the web. This position is the same as the position of Figure 6 since the paper webs are now in position for a typing operation.

Figure 11 is an elevational view of the mechanism for retaining the paper web pressure roll in engagement with the paper web, and is shown in released position.

Figure 12 is an elevational view of the mechanism shown in Figure 11, but in the engaged position.

Figure 13 is a perspective elevational view of the mechanism for adjusting the apparatus which measures the length of paper web passing through the carbon feeding apparatus.

Figure 14 is an elevational view of the indicator provided on the mechanism of Figure 13 for showing the length of paper web for which the machine is set to measure.

Figure 15 is a cross-sectional view, taken along line 15—15 of Figure 3, showing the adjusting means for securing the parts of the carbon holding platform in position with respect to one another.

Figure 16 is a cross sectional perspective view of the aligning mechanism with the web in position to be aligned.

Figure 17 is a cross sectional perspective view similar to Figure 16, showing the web in position when being aligned by the aligning mechanism.

Figure 18 is a cross sectional perspective view similar to Figure 17, showing the aligning mechanism being used as a tear-off mechanism.

The apparatus of this invention is adapted to be used in combination with a typewriter or printing machine wherein a plurality of paper webs is passed through the machine in adjacent relationship for producing multiple copies of desired information. Particularly, the apparatus is adapted to control the movement of carbon sheets which are placed between adjacent paper webs to produce the multiple copies. The paper webs have printed faces which are repeated upon the surface of the web to produce bill forms or the like which can be fed through a typewriter in a continuous web. The carbon sheets are adapted to be used several times and since the paper webs are continuous, the carbon sheets must be moved with respect to adjacent forms after the information has been placed upon one of the forms

so that the carbon sheets will be disposed adjacent the subsequent form upon the web when the form is carried over the platen of the typewriter. The webs can be arranged in a fan-fold pack with or without a perforated fold line to permit severance of individual forms from the webs, or they can be flat webs with a perforation line between adjacent form faces.

In this invention the carbon feeding apparatus 10 is constructed as an attachment which can be associated with any conventional typewriter. As shown in Figure 1, the carbon feeding apparatus 10 is shown in position adjacent a conventional typewriter 15. The typewriter 15 consists of the usual frame 11 supporting a carriage 12 which in turn supports a platen 13 having a knob 14 for rotating the platen 13 manually. The standard keyboard 16 is carried by the typewriter 15. In all respects the typewriter 15 is of conventional construction and it is therefore believed further description of this apparatus is not necessary. The association of the platen 13 and the carriage 12 of the typewriter with the carbon feeding apparatus 10 for producing cooperative action therebetween will be hereinafter more fully described.

The carbon feeding apparatus 10 consists of a frame 17 for supporting the carbon feeding apparatus 10 in adjacent relationship with respect to the typewriter 15. The frame 17 has a base 18 adapted to rest upon a table or other support. The base 18 has a cast body 19 secured thereto by means of a bolt 20. A bolt 21 is threaded into the body 19 and is adapted to engage some part of the rear wall of the frame 11 of the typewriter 15 for positioning the frame 17 and thus the carbon feeding apparatus with respect to the typewriter 15. A hook 22 is pivotally mounted on the body 19 by a pivot pin 23. The shank of the hook 22 extends through the pivot pin 23 into a threaded engagement with the thumb screw 24. The hook 22 is adapted to engage the rear wall of the frame 11 of the typewriter 15 at a point adjacent the bolt 21 to secure the frame 11 against the head of the bolt 21. The thumb screw 24 tightens the hook 22 upon the typewriter frame 11.

The frame 17 for the carbon feeding apparatus has two rods 25 and 26 extending transversely thereof and in parallel relationship. A frame 27 is carried upon the rods 25 and 26 by means of rollers 28 and 29 in engagement with the rods 25 and 26 respectively. The rollers 28 and 29 are suitably secured to the frame 27 and have arcuately curved surfaces 30 and 31 for engaging the surface of the rods 25 and 26. The frame 27 is thus supported vertically adjacent the rods 25 and 26 for movement along the rods as caused by the typewriter carriage in a manner to be hereinafter described. A U-shaped member 32 is secured to the frame 27 and extends around the rod 26 as a safety measure to prevent the rollers 28 and 29 from leaving the rods 25 and 26.

The frame 27 supports the bed plate 33 in the carbon feeding apparatus 10. The bed plate 33 is constructed in two parts consisting of an upper section 34 and a lower section 35. The upper bed plate section 34 is a flat plate having channel shaped edges 36 (see Figure 15). The lower bed plate 35 is also a flat plate having channel shaped edges 37 (see Figure 15) which are of sufficient dimension to encompass the channel shaped edges 36 of the upper bed plate 34 to permit the channel shaped edges 36 of the bed plate 34 to slide within the channel shaped edges 37 of the bed plate 35 whereby the longitudinal dimen-

sion of the bed plate 33 can be adjusted. The upper bed plate 34 is provided with recesses 38 extending longitudinally thereof and the lower bed plate 35 is provided with recesses 39 cooperating with the recesses 38 to aid the alignment between the two bed plate portions and to stiffen the same. The lower bed plate 35 has fingers 40 extending from the end thereof which project downwardly into the recess 38 in the upper bed plate portion 34 to prevent paper webs passing over the bed plate 34 from becoming entangled with the edge 41 of the lower bed plate portion 35.

The bed plate portions 34 and 35 are retained in properly adjusted relationship by means of a clamp 42 (see Figure 15). The clamp 42 is substantially U-shaped and has one arm 43 thereof in engagement with the channel shaped edge 36 of the bed plate portion 34. The opposite arm 44 engages a supporting plate 45 secured to the side of the bed plate portion 34 and has an ear 46 extending therethrough to prevent movement of the clamp 42 with respect to the plate 45. A threaded rod 47 extends from the clamp 42 through the plate 45. A thumb screw 48 is threaded upon the rod 47 for binding the channel shaped edges 36 and 37 of the bed plate portions 34 and 35 between the clamp 42 and the supporting plate 45.

The supporting plate 45 has a pair of threaded rods 49 extending therefrom upon which thumb screws 50 are threaded. The rods 49 slide within slots 51 provided in a supporting plate 52 extending from the frame 27 whereby the bed plate 33 is supported upon the frame 27 and can be adjusted vertically with respect to the same by proper location of the rods 49 within the slots 51 and binding the rods into position through means of the thumb screws 50. The bed plate 35 is provided with a supporting plate 45 adjacent each side edge thereof for engagement with a supporting plate 52 extending upwardly from the frame 27.

A paper guide member 53 extends from the lower bed portion 35 and is movable with respect to the same. This paper guide member 53 is provided with a rolled edge 54 which is positioned between the under side of the lower bed portion 35 and a retaining member 55. The retaining member 55 has a portion thereof in spaced parallel relationship to the bed plate portion 35 and has a hook portion 56 adapted to be engaged by the rolled edge 54 of the paper guide member 53 when it is desired to remove the paper guide member 53 from its adjacent position with respect to the back plate 57 of the typewriter. Normally, the paper guide 53 engages the back plate 57 to direct paper webs passing over the bed plate 33 toward the platen 13.

To provide connection between the carriage 12 of the typewriter and the bed plate 33 of the carbon feeding apparatus for moving the bed plate 33 in unison with the carriage 12 a frame 60 is provided. The frame 60 consists of a pair of arms 61 and 62 which are pivotally mounted upon pins 63 and 64 projecting from the supporting plates 45 secured to the upper bed plate portion 34. Helical springs 65 and 66 are positioned upon the pins 63 and 64 and have their inner ends in engagement with the arms 61 and 62 respectively. The spring 65 and 66 are retained under compression by means of screws 67 and 68 provided in the ends of the pins 63 and 64 respectively. The arms 61 and 62 are spaced from the supporting plates 45 to permit relative movement between the frame 60 and the bed

plate 33. The springs 65 and 66 are balanced so that the frame 60 floats upon the pins 63 and 64. This arrangement is such that the movement of the carriage 12 of the typewriter 15 is not transmitted directly to the bed plate 33 forcing the carriage of the typewriter to move the entire weight of the carbon feeding apparatus upon each successive motion, but rather the frame 60 moves with the carriage and through means of the floating action between the frame 60 and the bed plate 33, the bed plate 33 can follow up the movement of the frame 60 in a slightly lagging relationship.

The arms 61 and 62 of the frame 60 are connected together by means of a writing or erasing table 70 to maintain the arms in substantial parallel relationship. A tie rod 71 aids in holding the arms 61 and 62 in their proper relationship. A roller 72 is carried upon a plate 73 which is pivotally mounted upon the arm 61 by means of the pivot pin 74. The plate 73 has a pin 75 extending therefrom through a slot 76 provided in the arm 61. A thumb screw 77 is threaded upon the pin 75 to retain the plate 73 in a properly adjusted position. The roller 72 engages the platen 13 of the typewriter for supporting the frame 60 in adjacent relationship to the platen 13. Adjustment of the plate 73 permits adjustment of the frame 60 with respect to the platen 13. A similar roller 78 is provided upon the arm 62.

To retain the frame 60 in proper relationship with respect to the carriage 12 of the typewriter adjusting screws 79 and 80 are carried by the arms 61 and 62 respectively for engaging the side walls 35 or some stationary part of the carriage 12 of the typewriter. The frame 60 is thus positioned in stationary relationship with respect to the carriage 12 so that it will be moved with movement of the carriage 12.

Means is provided upon the frame 60 and between the arms 61 and 62 for arranging paper webs extending through the typewriter in longitudinally aligned relationship when a typed form is completed and is to be torn from the continuous web. This means consists of a pair of rollers 81 and 82 suitably mounted in the arms 61 and 62. The rollers are arranged in parallel relationship, the upper roller 82 having the extending shafts thereof disposed in the slots 175. A tear-off and web aligning blade 83 is pivotally carried upon an actuating lever 84 which is pivoted upon the pivot pin 85. One of the actuating levers 84 is provided upon each of the arms 61 and 62 of the frame 60 and is interconnected by means of a rod 86 to form the handle for the levers 84. A spring 87 is connected between the lever 84 and either of the arms 61 and 62 to retain the tear-off and aligning blade 83 out of engaged relationship with respect to the rollers 81 and 82 whereby paper webs can pass freely between the tear-off and aligning blade 83 and the rollers 81 and 82.

To retain the paper webs passing over the bed plate 33 in engagement therewith and to prevent buckling of the paper when the webs are moved in a reverse direction by means of the platen 13 of the typewriter a paper bale 88 is placed in engagement with the lower bed plate portion 35. The paper bale 88 consists of a wire frame 89 having a plate 90 secured to adjacent parallel arms 91 and 92 of the frame 89. A leaf spring 93 is secured to the plate 90 and is adapted to extend angularly upwardly therefrom. The free end of the leaf spring 93 has an upwardly bent portion 94 which forms an angle with respect to the main body of the leaf spring 93 to form a

V-shaped channel which engages the writing table 70. The upward tension of the leaf spring 93 retains the bale 88 in engagement with the bed plate 33. The degree of tension of the paper bale upon the bed plate 33 can be regulated by means of an adjusting screw 95 which is in threaded engagement with the leaf spring 93 and bears against the plate 90 of the paper bale 88. A pointer 176 is slidably carried upon the bale 88 so that it is adapted to be positioned upon the bale so that it will provide means whereby an operator can gauge the position of a fold or perforation line with respect to the tear-off or aligning blade 83.

When a completed form is to be removed from the continuous web of forms the platen 13 is rotated by the operator to feed the webs 142, 143 and 144 downwardly over the bed plate 33 and upwardly past the rollers 81 and 82 until a perforation or fold line in the web is in alignment with the pointer 176. A fold line 180 is then in position adjacent the tear-off and aligning blade 83 as shown in Figure 16. The blade 83 is then moved inwardly against the webs, the blade being directed somewhat downwardly toward the roller 81 to engage the webs 142, 143 and 144 in a manner that they will be caused to shift with respect to one another when the webs are retained between the blade 83 and the roller 81 and the blade rides upwardly over the surface of the roller 81, as shown in Figure 17. The blade 83 strikes the perforation or fold line in the webs and thus causes them to shift and be aligned thereby.

The blade 83 is then retained in position as shown in Figure 18 so that when an operator grasps the forms extending above the roller 83 they can be pulled forwardly to sever the forms from the webs, the upper roll 83 moving upwardly to prevent binding of the forms between the rollers 81 and 82.

The carbon feeding mechanism consists of a roller 96 bearinged in a U-shaped support bracket 97 which is secured to the under side of the upper bed plate portion 34. The surface of the roller 96 is positioned adjacent an opening 98 provided in the uppermost edge of the bed plate 34 which is adapted to be engaged by a paper web for rotating the roller 96 when the web is moved inwardly into engagement with the roller 96 by means of a roller 132. The roller 96 has a spur gear 99 secured upon the same shaft which bearing the roller 96, the spur gear 99 thus rotates with the roller 96. The spur gear 99 is in meshing relationship with a spur gear 100 bearinged in the support bracket 97 by means of the shaft 101. The gear 100 carries a pin 102 adapted to engage an arm 103 carried upon a shaft 104. The shaft 104 (see Figure 3) is bearinged at its inner end upon the shaft 101 which extends within an axle bore provided in the shaft 104. The opposite end of the shaft 104 extends within an adjusting mechanism for regulating the operation of the carbon feed in accordance with the length of form being used upon the same, which mechanism will be hereinafter described. The arm 103 is secured to the shaft 104 by means of a clamp 105 and is thus stationary with respect to the gears 100 unless rotated by the shaft 104. A torsion spring 106 surrounds the shaft 101 and has one end thereof in engagement with the support bracket 97 and the opposite end secured to the gear 100 whereby the gear is constantly urged in a direction to place the pin 102 against the arm 103.

A carbon detent 107 is secured adjacent each end of a rod 108 bearinged in the depending wall 109 of the upper bed portion 34. The carbon detents 107 are secured to the rod 108 by means of clamps 110. The detents 107 extend through slots 111 provided in the upper bed portion 34 whereby the ears 112 are adapted to be engaged by carbon bars 113 (see Figures 6 to 10) which carry carbon sheets 114 adapted to be positioned between adjacent continuous paper webs. Each of the detents 107 carries a dog 115 pivoted thereto by means of a pin 116. A light spring is positioned between the dog 115 and the ear 112 extending upwardly from the detent 107 to urge the dog 115 in a forward position (as shown in Figure 4).

The carbon detent 107 has a ledge 118 adapted to engage a finger 119 provided on a clamp 120 secured to a rod 121 bearinged in the depending side wall 109 of the upper bed portion 34. The clamp 120 forms a lever extending from the rod 121. A clamp 122 is secured to the rod 121 from a lever extending therefrom adapted to be engaged by the pin 102 secured to the spur gear 100. The clamps 120 and 122 provide a lever system between the pin 102 and the carbon detent 107 whereby the carbon detent is released when the pin 102 engages the clamp 122 to cause rotation of clamp 120 with respect to the carbon detent 107.

The shaft 108 to which the carbon detent 107 is secured has a clamp 123 secured thereto forming a lever extending therefrom. The clamp 123 has an arm 124 pivotally connected thereto by means of a pin 125 which extends into engagement with a clamp 126, the lever 124 being pivoted to the clamp 126 by means of the pin 127 (see Figure 5). The clamp 126 is carried upon an arm 128 extending inwardly from a wire frame 129. The clamp 126 in this instance remains sufficiently loose upon the arm 128 to be bearinged thereon. A clamp 130 is secured to the arm 128 of the frame 129 and has a pin 131 extending therefrom into engagement with the bearinged clamp 126.

The frame 129 carries a roller 132 positioned in substantially vertical alignment with the roller 96 to apply friction upon a paper web passing between the rollers 132 and 96. The weight of the roller 132 and the frame 129 is such that the pin 131 normally engages the bearinged clamp 126 so that the clamps 126 and 130 actuate the frame 129 as though the arm 124 was connected directly to the frame 129 for rotating the same about the arm 128 as an axis.

If, however, it is desired to prevent the roller 132 from engaging the paper web, the mechanical arrangement provided by the clamps 126 and 130 permit the frame 129 to be moved rearwardly manually with respect to the operating mechanism. A stop 133 pivoted upon a support member 134 by means of a pin 134a (see Figure 4) is thrown rearwardly to permit the frame 129 to pass thereover and thus be thrown away from engagement with the paper web passing over the roller 96.

The support member 134 is adapted to engage the edge of paper webs passing over the bed portion 34 to maintain edge alignment between the webs. These support members 134 are adjustable transversely of the bed portion 34 within slots 153 provided in the bed portion 34.

When paper webs, which have been folded in accordion fashion, are passed over the upper edge 75 of the bed plate 34, there is a tendency for the

folds in the webs to cause the roller 132 to lift sufficiently that slippage is permitted between the roller 96 and the paper webs whereby the measuring device is not properly operated. To maintain the roller 132 in engagement with the paper webs a locking mechanism is provided for engaging the operating mechanism for the roller 132 when the paper webs are moving in engagement with the roller 96. When the paper webs are moving over the roller 96 the position of the carbon feeding apparatus is as shown in Figures 4 and 8.

The locking mechanism for the roller 132 consists of an arcuately shaped arm 135 secured to a clamp member 136 which in turn is secured to the shaft 121 (see Figures 11 and 12). The frame 129 carries a clamp 137 secured thereto and having a pin 138 extending therefrom. The arm 135 has a hook 139 adapted to engage the pin 138 to retain the frame 129 in position with the roller 132 in engagement with the paper web passing over the roller 96. The arm 135 is rotated with the shaft 121 as the axis of rotation so that when the shaft 121 rotates to position the carbon detent 107 in the position shown in Figures 1 and 7, the roller 132 is thereby placed in engagement with the paper webs passing over the roller 96, causing them to engage the roller 96 to drive the same, the hook 139 being advanced into engagement with the pin 138 thereby locking the frame 129 in position with the roller 132 engaging the paper web.

To manually release the locking mechanism (shown in Figures 11 and 12) a finger pad 140 is provided on the arm 135. By applying pressure upon the finger pad 140 the shaft 121 will be rotated about its axis in a rightward direction (as viewed in Figures 11 and 12) to release the pin 125 and thereby permit the roller 132 to be lifted from the paper webs.

The description heretofore presented sets forth the mechanical arrangement of the carbon feeding apparatus. The diagrammatic figures, 6 to 10, show the apparatus in various stages of operation. The mechanism is shown in various positions resulting from various movements and operation of the apparatus. The mechanism shown in these figures is somewhat schematic but the operational function is completely set forth.

Beginning with Figure 6, the apparatus is shown in a position wherein a typing operation can be performed upon a plurality of adjacent paper webs 142, 143 and 144 having carbon sheets 114 interleaved therebetween. The carbon sheets 114 in this figure are shown in position for the typing operation and have been previously released from the carbon detent 107 to permit the carbon bars 113 and the carbon sheets 114 to move with the paper webs 142, 143 and 144, as fed through the typewriter by means of pressure engagement between the platen 13 and the pressure rollers 141 of the typewriter 15.

When the typing operation has been completed upon one of the forms printed on the face of the paper webs 142, 143 and 144 the carbon sheets 114 must be returned upon the bed plate 33. To perform this operation the platen 13 is rotated in the direction of the arrow shown in Figure 7 whereby the paper webs 142, 143 and 144 are moved upwardly over the bed plate 33 carrying the carbon sheets 114 and the carbon bars 113. When the carbon bars 113 strike the dogs 115 the carbon detent 107 is rotated about the axis of the shaft 108, and since the detent 107 is secured to the shaft 108 the clamp 123 is rotated in the

direction of the arrow shown in Figure 7. The ear 112 of the carbon detent 107 rises into the position shown in Figure 7 to position itself in the path of the downward travel of the carbon bars 113 when their travel is reversed by reversing rotation of the platen 13. Rotation of the clamp 123 positions the arm 124 to cause rotation of the frame 129 in the direction of the arrow shown in Figure 7 whereby the roller 132 is caused to engage the paper webs 142, 143 and 144 and move them into engagement with the roller 96. As can be seen from the position of the linkage between the shaft 108 and the frame 129 a toggle arrangement is provided thereby so that when the apparatus is in the position shown in Figure 7 there is a tendency for the carbon detent 107 to be retained in the position shown therein.

When the carbon detent 107 reaches the position shown in Figure 7 the lever linkage provided by the clamps 120 and 122 on the shaft 121 tends to rotate in a rightward direction, as indicated by the arrow, due to the off-balance of the linkage in that direction whereby the finger 119 provided on the clamp 120 is positioned beneath the ledge 118 provided on the carbon detent 107 to lock the detent in the position shown in Figure 7. Also, the arm 135 engages the pin 138 as shown in Figure 12 to lock the roller 132 in position as shown in Figures 7 and 12.

The paper webs are moved rearwardly or upwardly along the bed plate 33 until the above described operation is performed. If the operator of the typewriter should run the typed form from between the platen 13 and the pressure rollers 141 a slight buckle will be given the paper webs (as shown at 154) to provide sufficient spring in the webs to force the ends thereof into engagement with the platen 13 and the pressure roller 141 so that when the direction of rotation of the platen 13 is reversed the paper webs will be caught between the platen 13 and the pressure roller 141 to again send the same through the typewriter.

The mechanism is now in position to permit passage of the paper webs 142, 143 and 144 over the bed plate 33 without movement of the carbon sheets 114 so that the form which has been previously typed can be removed from the typewriter and a subsequent form aligned. The beginning of this operation is shown in Figure 8. The showing of this figure is such that the platen 13 is rotating in the direction of the arrow, thereby moving the paper webs 142, 143 and 144 through the typewriter, but the carbon sheets 114 are detained from movement since the carbon bars 113 are in engagement with the ear 112 of the carbon detent 107. It will be remembered that the roller 132 is in engagement with the paper webs passing over the roller 96 so that the roller 96 will be rotated by movement of the paper thereover, due to the frictional engagement of the paper webs with the roller 96. Rotation of the roller 96 causes the gear 100 to be rotated so that the pin 102 will be advanced in a leftward direction, as indicated by the arrow in Figure 8. The pin 102 would be advanced until it strikes the end of the clamp 122 rotating the shaft 121 and the clamp 120 in a leftward direction until the finger 119 on the clamp 120 is moved out of engagement with the ledge 118 on the carbon detent 107. The quantity of paper web passing over the roller 96 before the carbon detent 107 releases the carbon bars 113 is equal to the length of a printed form face and is measured by the travel of the pin 102 from the arm 103 to the

clamp 122. The interval of time required for the pin to move from the arm 103 to the clamp 122 and release the detent 107 thus regulates the length of paper web moved through the carbon sheets 114 before they are released to permit their movement with the paper webs 142, 143 and 144.

Movement of the paper webs 142, 143 and 144 over the carbon sheets 114 and the carbon bars 113 produces friction tending to move the carbon bars downwardly and thus move the carbon sheets with the paper webs. However, the carbon bars cannot move until the pin 102 has engaged the clamp 122 and has rotated the clamp 120 sufficient to release the carbon detent 107. When the carbon detent 107 is released, frictional engagement between the paper webs and the carbon sheets will rotate the carbon detent 107 about the axis of the shaft 108 thereby causing movement of the arm 124 which results in lifting the roller 132 from engagement with the paper webs passing over the roller 96. Release of pressure upon the paper webs passing over the roller 96 stops rotation of the roller 96 since the webs are released from engagement with the surface of the roller and will now be supported by the bed plate 34 in spaced relationship to the roller 96. The linkage between the carbon detent 107 and the frame 129 is such that the combined weight of the roller 132 and the frame 129 retains the mechanism in the position shown in Figure 9 since the arm 124 and the clamp 123 have now been thrown over center from the position shown in Figure 8.

When the pressure is released from the paper webs the torsion spring 106 rotates the gear 100 to return the pin 102 against the arm 103 so that the measuring device is conditioned for the next operation.

The carbon sheets and the paper webs are now ready for advancement through the typewriter by means of the platen 13 and the pressure rollers 141 to permit the typed form to be removed from the machine, to align a subsequent form and to position the subsequent form in typing position upon the platen 13. The transition from Figure 9 to Figure 10 shows the paper webs advanced through the typewriter until a perforation or fold line between adjacent forms is adjacent the tear off blade 83. The operator rotates the platen 13 until a perforation or fold line is aligned with the pointer 176. This places a fold or perforation line adjacent the blade 83 as shown in Figure 16. At this time the pressure rollers 141 of the typewriter are released from engagement with the paper webs passing under the platen 13. The blade 83 is then moved inwardly to engage the webs and align them. This is accomplished since the fold line between adjacent form faces is the weakest portion of the form and the adjacent folds will always tend to align one with the other when a sharp edged instrument engages the fold line and moves the same thereby.

The previously typed forms, now positioned above the tear off blade, can be torn from the main body of the paper webs. The tear off blade 83 is now released and the pressure rollers 141 again brought into engagement with the paper webs passing under the platen 13. The platen 13 can then be rotated in the usual manner to align the new form in proper position for the next typing operation. The process is then repeated by returning to the beginning of the cycle, as indicated in Figure 6.

As heretofore mentioned the position of the

arm 103 with respect to the clamp 122, and thus the travel of the pin 102 regulates the length of paper web which passes between the carbon sheets 114 before they are again released to permit their advancement with the paper webs. To adjust the position of the arm 103 the mechanism shown in Figure 13 is provided.

This mechanism consists of a worm wheel 145 secured upon the shaft 104 which carries the arm 103 (as shown in Figure 3). The worm wheel 145 carries a pointer 146 having an edge thereof adjacent a slot 147 provided in the cover 148 for the adjusting mechanism. A worm 149 is in engagement with the worm wheel 145 and is carried upon a shaft 150 bearinged in the cover 148. A hand wheel 151 is secured to the shaft 150 and is disposed beneath an indicating pointer 152. Indices are placed upon the hand wheel 151 indicating fractions of an inch so that one rotation of the hand wheel 151 causes rotation of the shaft 104 to position the arm 103 further from or closer to the clamp 122 to shorten or lengthen the form passing over the roller 96 before release of the carbon detent 107. One rotation of the wheel 151 thus changes the setting of the arm 103 to permit one inch more or one inch less of web to pass over the roller 96 until the carbon bars are released.

Rotation of the worm wheel 145 moves the pointer 146 to indicate the number of revolutions of the hand wheel 151 and thus the number of inches which can pass over the wheel 96 before the carbon detent 107 releases the carbon bars 113. The indices adjacent the slot 147 thus indicate inches in length of the paper web so that by reading a combination of the indices adjacent the slot 147 and the indices on the hand wheel 151 an exact determination can be had of the length of form for which the carbon feeding mechanism is set.

In order to use the typewriter in normal typing operation for single sheet work the frame 60 can be pivoted upwardly upon the pins 63 and 64 so that the frame will lie upon the bed plate 33. The paper bale 88 is removed from the carbon feeding apparatus to permit the pivotal movement of the frame 60. The paper guide 53 is then moved upwardly until the rolled edge 54 engages the hook portion 56 of the retaining member 55. When these operations have been performed the space above the typewriter platen 13 and the back plate 57 of the typewriter is free and unobstructed so that paper sheets can be fed into the typewriter in the normal manner.

Having thus fully described my invention what I claim as new and desire to secure by Letters Patent is:

1. In a paper handling apparatus, means for supporting a plurality of paper webs in juxtaposed relationship, means for supporting carbon sheets adapted to be interleaved between the paper webs, means for detaining movement of the carbon sheets when the paper webs move over said supporting means, means for locking said detaining means in the detaining position, and means actuated by movement of said paper webs with respect to said supporting means for unlocking said locking means after a predetermined length of paper web has passed over said supporting means, said locking means thereby releasing said detaining means to permit the carbon sheets to thereafter move with the paper webs.

2. In a paper handling apparatus, means for supporting a plurality of paper webs in juxtaposed relationship, means for supporting carbon

75

sheets adapted to be interleaved between the paper webs, means for detaining movement of the carbon sheets when the paper webs move over said supporting means, means for locking said detaining means in the detaining position, means actuated by movement of said paper webs with respect to said supporting means for unlocking said locking means after a predetermined length of paper web has passed over said supporting means, said locking means thereby releasing said detaining means to permit the carbon sheets to thereafter move with the paper webs, and means engaged by said carbon sheet supporting means when the carbon sheets and paper webs are moved in a reverse direction to the direction of initial movement for actuating said detaining means to place the same in the detaining position.

3. In a paper handling apparatus, means for supporting a plurality of paper webs in juxtaposed relationship, means for supporting carbon sheets adapted to be interleaved between the paper webs, means for detaining movement of the carbon sheets when the paper webs move over said supporting means, means for locking said detaining means in the detaining position, means actuated by movement of said paper webs with respect to said supporting means for unlocking said locking means after a predetermined length of paper web has passed over said supporting means, said locking means thereby releasing said detaining means to permit the carbon sheets to thereafter move with the paper webs, means engaged by said carbon sheet supporting means when the carbon sheets and paper webs are moved in a reverse direction to the direction of initial movement for actuating said detaining means to place the same in the detaining position, said locking means thereafter moving into locking position to retain said detaining means in the detaining position.

4. In a paper handling apparatus, means for supporting a plurality of paper webs in juxtaposed relationship, means for supporting carbon sheets adapted to be positioned between adjacent paper webs, means for detaining movement of the carbon sheets when the paper webs are moved upon the supporting means, means for locking said detaining means in the detaining position, means for releasing said locking means, means for actuating said releasing means, said actuating means being engaged by the paper webs passing over the supporting means, said releasing means actuating said locking means to unlock said detaining means when a predetermined length of paper web has passed over the actuating means for said releasing means.

5. In a paper handling apparatus, means for supporting a plurality of paper webs in juxtaposed relationship, means for supporting carbon sheets adapted to be positioned between adjacent paper webs, means for detaining movement of the carbon sheets when the paper webs are moved upon the supporting means, means for locking said detaining means in the detaining position, means for releasing said locking means, means for actuating said releasing means, said actuating means being engaged by the paper webs passing over the supporting means, said releasing means actuating said locking means to unlock said detaining means when a predetermined length of paper web has passed over the actuating means for said releasing means, and means for maintaining frictional engagement of the paper webs with said actuating means when said actuating means is operating said releasing means.

6. In a paper handling apparatus, means for supporting a plurality of paper webs in juxtaposed relationship, means for supporting carbon sheets adapted to be positioned between adjacent paper webs, means for detaining movement of the carbon sheets when the paper webs are moved upon the supporting means, means for locking said detaining means in the detaining position, means for releasing said locking means, means for actuating said releasing means, said actuating means being engaged by the paper webs passing over the supporting means, said releasing means actuating said locking means to unlock said detaining means when a predetermined length of paper web has passed over the actuating means for said releasing means, and means for maintaining frictional engagement of the paper webs with said actuating means when said actuating means is operating said releasing means, said last mentioned means releasing frictional engagement of the paper webs upon said actuating means when said releasing means operates said locking means to unlock said detaining means.

7. In a paper handling apparatus, means for supporting a plurality of paper webs in juxtaposed relationship, means for supporting carbon sheets adapted to be positioned between adjacent paper webs, means for detaining movement of the carbon sheets when the paper webs are moved upon the supporting means, means for locking said detaining means in the detaining position, means for releasing said locking means, means for actuating said releasing means, said actuating means being engaged by the paper webs passing over the supporting means, said releasing means actuating said locking means to unlock said detaining means when a predetermined length of paper web has passed over the actuating means for said releasing means, and means actuated by said detaining means for applying pressure upon the paper webs to cause frictional engagement thereof upon said actuating means while said detaining means is in the detaining position.

8. In a paper handling apparatus, means for supporting a plurality of paper webs in juxtaposed relationship, means for supporting carbon sheets adapted to be positioned between adjacent paper webs, means for detaining movement of the carbon sheets when the paper webs are moved upon the supporting means, means for locking said detaining means in the detaining position, means for releasing said locking means, means for actuating said releasing means, said actuating means being engaged by the paper webs passing over the supporting means, said releasing means actuating said locking means to unlock said detaining means when a predetermined length of paper web has passed over the actuating means for said releasing means, and means actuated by said detaining means for applying pressure upon the paper webs to cause frictional engagement thereof upon said actuating means while said detaining means is in the detaining position; said detaining means actuating said pressure applying means to release pressure from the paper webs when said detaining means is unlocked from the detaining position by said releasing means.

9. In a paper handling apparatus, means for supporting a plurality of paper webs in juxtaposed relationship, means for supporting carbon sheets adapted to be positioned between adjacent paper webs, means for detaining movement of the carbon sheets when the paper webs are moved upon the supporting means, means for locking

said detaining means in the detaining position, means for releasing said locking means, means for actuating said releasing means, said actuating means being engaged by the paper webs passing over the supporting means, said releasing means actuating said locking means to unlock said detaining means when a predetermined length of paper web has passed over the actuating means for said releasing means, and means actuated by said detaining means for applying pressure upon the paper webs to cause frictional engagement thereof upon said actuating means while said detaining means is in the detaining position, said detaining means actuating said pressure applying means to release pressure from the paper webs when said detaining means is unlocked from the detaining position by said releasing means, said releasing means being actuated by said actuating means after a predetermined length of paper web has passed over said actuating means.

10. A paper handling apparatus comprising a bed adapted to support a plurality of paper webs in juxtaposed relationship and carbon sheets interleaved between the paper webs, a carbon sheet 5 detent extending through said bed and retractable with respect to the surface of said bed, pivoted lever means for locking said detent in position for detaining carbon sheets, means movable with respect to said lever means for pivoting the same to release said detent, and means for moving said last mentioned means toward said lever means in response to movement of the paper web over said bed.

11. A paper handling apparatus comprising a bed adapted to support a plurality of paper webs in juxtaposed relationship and carbon sheets interleaved between the paper webs, a carbon sheet 10 detent extending through said bed and retractable with respect to the surface of said bed, pivoted lever means for locking said detent in position for detaining carbon sheets, means movable with respect to said lever for pivoting the same to release said detent, means for moving said last mentioned means toward said lever means in response to movement of the paper web over said bed, and means for returning said movable means to its initial starting position after releasing said 15 detent from said lever means.

12. A paper handling apparatus comprising a bed adapted to support a plurality of paper webs in juxtaposed relationship and carbon sheets interleaved between the paper webs, a carbon sheet 20 detent extending through said bed and retractable with respect to the surface of said bed, pivoted lever means for locking said detent in position for detaining carbon sheets, means movable with respect to said lever means for pivoting the same to release said detent, means for moving said last mentioned means toward said lever means in response to movement of the paper web over said bed, means for returning said movable means to its initial starting position after releasing said 25 detent from said lever means, stop means for determining the starting position of said movable means, and means for changing the position of said stop means to change the length of travel of said movable means and thus the length of paper web passing over said bed before said detent is released from said lever means.

13. A paper handling apparatus comprising a bed adapted to support a plurality of paper webs in juxtaposed relationship and carbon sheets in-

terleaved between the paper webs, a carbon sheet 25 detent extending through said bed and retractable with respect to the surface of said bed, pivoted lever means for locking said detent in position for detaining carbon sheets, means movable with respect to said lever means for pivoting the same to release said detent, means for moving said last mentioned means toward said lever means in response to movement of the paper web over said bed, and means carried by said detent and extending through said bed adapted to be engaged upon return movement of the carbon sheets from the initial direction of movement thereof to cause said detent to project through said bed, thereby 30 placing said detent in detaining position.

14. A paper handling apparatus comprising a bed adapted to support a plurality of paper webs in juxtaposed relationship and carbon sheets interleaved between the paper webs, a carbon sheet 35 detent extending through said bed and retractable with respect to the surface of said bed, pivoted lever means for locking said detent in position for detaining carbon sheets, means movable with respect to said lever means for pivoting the same to release said detent, means for moving said last mentioned means toward said lever means in response to movement of the paper web over said bed, and means carried by said detent and extending through said bed adapted to be engaged upon return movement of the carbon sheets from the initial direction of movement thereof to cause said detent to project through said bed, thereby 40 placing said detent in detaining position, said lever means dropping by gravity into position in engagement with said detent to lock the same in said position.

15. A paper handling apparatus comprising a bed adapted to support a plurality of paper webs in juxtaposed relationship and carbon sheets interleaved therebetween, a detent pivoted adjacent said bed and extending through said bed for engaging the carbon sheets interleaved between paper webs supported upon said bed, lever means 45 pivotally mounted adjacent said detent for locking said detent in detaining position, roller means adapted to be engaged by the paper webs supported upon said bed, and release means driven by said roller means for moving said lever means to release said detent.

16. A paper handling apparatus comprising a bed adapted to support a plurality of paper webs in juxtaposed relationship and carbon sheets interleaved therebetween, a detent pivoted adjacent 50 said bed and extending through said bed for engaging the carbon sheets interleaved between paper webs supported upon said bed, lever means pivotally mounted adjacent said detent for locking said detent in detaining position, roller means adapted to be engaged by the paper webs supported upon said bed, and release means driven by said roller means for moving said lever means to release said detent, said roller means being rotated by movement of the paper webs over said bed upon engagement of said webs with said roller means, whereby movement of said release means with respect to said lever means determines the length of paper web moving over said bed before said lever means releases said detent.

17. A paper handling apparatus adapted to be used in combination with a printing or typing machine having a platen supported by a movable carriage comprising a frame, means for securing said frame to a typing or printing machine, a bed for supporting a plurality of paper

webs in juxtaposed relationship, roller means supporting said bed upon said frame to permit movement of said bed with respect to said frame, and means resiliently supported upon said bed and extending therefrom adapted to be supported by the platen of the printing or typing machine and having means to engage the carriage of said machine.

18. A paper handling apparatus adapted to be used in combination with a printing or typing machine having a platen supported by a movable carriage comprising, a frame, means for securing said frame to a typing or printing machine, a bed for supporting a plurality of paper webs in juxtaposed relationship, roller means supporting said bed upon said frame to permit movement of said bed with respect to said frame, a second frame extending from said bed, pivot means on said bed for supporting said second frame, roller means carried by said second frame and adapted to engage the platen of the typing or printing machine to support said second frame adjacent the platen, means on said second frame for engaging the carriage of the typing or printing machine to cause movement of said frame with said carriage, and resilient means supporting said second frame upon said pivot means to prevent direct transmission of carriage movement to said bed.

19. A paper handling apparatus adapted to be used in combination with a printing or typing machine having a platen supported by a movable carriage comprising, a frame, means for securing said frame to a typing or printing machine, a bed for supporting a plurality of paper webs in juxtaposed relationship, roller means supporting said bed upon said frame to permit movement of said bed with respect to said frame, a second frame extending from said bed, pivot means on said bed for supporting said second frame, roller means carried by said second frame and adapted to engage the platen of the typing or printing machine to support said second frame adjacent the platen, means on said second frame for engaging the carriage of the typing or printing machine to cause movement of said second frame with said carriage, said second frame being movable upon said pivot means to permit the

same to be lifted from said platen and supported upon said bed, whereby the space above said platen is cleared of obstructions from the paper handling apparatus.

5 20. A paper handling apparatus adapted to be used in combination with a printing or typing machine having a platen supported by a movable carriage comprising, a frame, means for securing said frame to a typing or printing machine, a bed for supporting a plurality of paper webs in juxtaposed relationship, roller means supporting said bed upon said frame to permit movement of said bed with respect to said frame, a second frame extending from said bed, pivot means on said bed for supporting said second frame and adapted to engage the platen of the typing or printing machine to support said second frame adjacent the platen, means on said second frame for engaging the carriage of the typing or printing machine to cause movement of said frame with said carriage, a paper bale engaging said bed having means engaging said second frame to support said bale in position upon said bed, said bale being removable from said bed and said second frame and said second frame being movable upon said pivot means to permit the same to be lifted from said platen and supported upon said bed, whereby the space above said platen is cleared of obstructions from the paper handling apparatus.
